UNITED STATES PATENT OFFICE.

FERDINAND L. HOLLWEG AND CLARENCE FIRTH, OF INDIANAPOLIS, INDIANA,
ASSIGNORS TO MUTUAL CHINA CO., OF INDIANAPOLIS, INDIANA, A CORPOR-
ATION OF INDIANA.

DESIGN FOR A CHINA TABLEWARE ARTICLE.

52,653.

Specification for Design.

Patented Nov. 12, 1918.

Application filed August 18, 1917. Serial No. 187,027. Term of patent 7 years.

To all whom it may concern:

Be it known that we, FERDINAND L. HOLLWEG and CLARENCE FIRTH, citizens of the United States, residing at Indianapolis, in the county of Marion and State of Indiana, have invented a new, original, and ornamental Design for a China Tableware Article, of which the following is a specification, reference being had to the accompanying drawing, forming part hereof.

In such drawing, the single figure is a fragmentary plan view of a plate, showing our new design. Such a plate is an example of the china tableware articles, including dishes of all kinds as well as plates, to which our new design is embodied.

According to our new design a china tableware article is provided with a scalloped line

close to the edge thereof, a regular line removed from such edge, radial lines connecting the scalloped and regular lines at the points where the scalloped line comes nearest to the regular line, thus providing panels, and a conventional flower in each panel as shown, all these being colored in contrast to the chinaware.

We claim:

The ornamental design for a china tableware article, as shown and described.

In witness whereof, we have hereunto set our hands at Indianapolis, Indiana, this sixteenth day of August, A. D. one thousand nine hundred and seventeen.

FERDINAND L. HOLLWEG.
CLARENCE FIRTH.
